Patented Apr. 18, 1899.

J. H. DAVIS.

APPARATUS FOR PAINTING.

(Application filed Oct. 3, 1898.)

(No Model.)

FIG. 1.

FIG. 2.

WITNESSES:

Robert W. McCulloch

Alfred Meltzer

INVENTOR

John H. Davis,
BY
W. R. Rummel
his ATTORNEY.

UNITED STATES PATENT OFFICE.

JOHN H. DAVIS, OF CHICAGO, ILLINOIS, ASSIGNOR OF TWO-THIRDS
TO LORENZO L. MERRIMAN, ALBERT E. JESSURUN, AND WILLIAM
R. RUMMLER, OF SAME PLACE.

APPARATUS FOR PAINTING.

SPECIFICATION forming part of Letters Patent No. 623,307, dated April 18, 1899.

Application filed October 3, 1898. Serial No. 692,474. (No model.)

To all whom it may concern:

Be it known that I, JOHN H. DAVIS, a citizen of the United States of America, and a resident of the city of Chicago, in the county 5 of Cook and State of Illinois, have invented certain new and useful Improvements in Apparatus for Painting, of which the following is a specification.

My invention relates to the method of and 10 apparatus for painting described in my Letters Patent, dated January 31, 1899, No. 618,788, and has particular reference to the means for feeding the paint upon the supporting liquid.

The main objects of my present invention 15 are to provide for making the films or coatings which are formed upon the supporting liquid of different variegated and mottled designs and to provide for controlling the general character of the design on each film. I 20 accomplish these objects by the apparatus illustrated in the accompanying drawings, in which—

Figure 1 is a top plan of a device embodying my invention, and Fig. 2 is a partly-sectional elevation of the same.

The tank 27 for containing the paint-supporting liquid is shown mainly broken away, and the surface of the liquid is indicated by the line *a*.

30 The paint pots or receptacles 2 are supported by brackets 1' on the member 1 of the frame. The member 1 is shown partly broken away. This will be secured in any suitable manner above the tank containing the supporting liquid. The pots 2 are essentially the same, but carry feeders of different form. Each pot has a plunger-head 3 therein, supported by an arm 4, carrying a weight 5 and fastened by a pin 6" to the lever 6, which is 35 fulcrumed at 6' on an arm 2', secured to the upper part of the pot. The cams 7 are rigid on the shafts 8, which are journaled in arms 8' on the member 1 of the frame.

Each shaft 8 is connected with suitable 40 driving power for revolving same. (Not shown in the drawings.)

It will be seen that the revolution of the shafts 8 through the cams 7, acting under the free ends of the levers 6, intermittently raises

the plunger-heads 3, the weights 5 urging 50 same normally downwardly. The office of the plunger-heads is to keep the paint agitated and in free-flowing condition.

The parts below the cocks 9 and 9' control the variety of the designs in which the paint 55 forms upon the supporting liquid. In the form shown at the right of Fig. 2 a tube 10 is threaded to the cock 9. The tube carries a wick 11, made of coarsely-woven wool, spun yarn, or other similar material. The wick 60 reaches just into the surface *a* of the supporting liquid and furnishes a steady unbroken flow of paint, which, through the current of the supporting liquid, forms a streaky coating upon same. This coating is carried 65 by the current in the direction of the arrow. The next feeder has a grooved needle 12, fastened to the lever 13, which is fulcrumed at 14 on the arm 15 of the frame. The needle 12 is flared at the upper end in funnel shape, 70 so as to catch the paint dropping from the cock 9'. The free arm of the lever 13 is urged normally downward by the spring 16, secured to the same and to the arm 15. The cam 17 is rigidly mounted on the shaft 17', 75 journaled in the arm 15. The shaft 17' is connected with suitable driving power for revolving same. (Not shown in the drawings.) The shafts 8 and 17' may all be connected by pulleys so as to be driven simultaneously. The cam 17 intermittently raises 80 the free end of the lever 13 against the action of the spring 16, so as to give the needle 12 a vibratory motion, as indicated by the dotted lines. This scatters the paint in drops 85 from the end of the needle, the same running down the groove in the side of the needle. The drops from the needle spread out in different shapes, sinking into the film already formed and some running together, so as to 90 form a marbled surface in connection with the ground color furnished by the feeder to the right, before described.

The feeder at the left of Fig. 2 is in the form of an atomizer. This consists of a funnel 18, secured to the pipe 20 below the cock 9. The pipe 20 communicates with the air-chamber 21, which is supported on the mem-

ber 21' of the frame. The cover of the air-chamber is a flexible diaphragm 22, which is held normally upward by the spring 23 in the position indicated by the dotted line. A weight or plunger 24 is suspended above the diaphragm by the arm 25, which is slidingly supported in the bearing-sleeve 25' in the member 1 of the frame. The upper end of the arm 25 is curved, so as to permit the free rotation of the cam 7, and projects over same and under the free end of the lever 6 at 26. The pipe 20 has an extension 19, curved slightly upward and forming a drip-pan under the funnel 18.

15 It will be seen that when the plunger 24 is raised by the action of the cam 7 the chamber 21 fills with air, and when the plunger drops upon the diaphragm the air is suddenly expelled through the pipe 20, so as to scatter the paint dropping from the funnel in fine spray, which settles into the coating already formed by the other feeders. This being of a different color gives same the appearance of a fine cross-grain. The film is so thin that 25 when pigments of about the same specific gravity are used its appearance will be the same on both sides, so that an article treated by bringing same in contact with the upper surface of the film will show in reverse the 30 same design as that presented toward the article.

It will be seen that the different forms of feeders may be used singly or in combination and that the extent of flow from each may be 35 regulated by the cocks, so that an innumerable variety of films may be formed. The speed and direction of the current will also influence the character of the design. When a certain current is used and the feeders have 40 a certain adjustment, the film formed thereby will have the same general character throughout, though varying in the specific designs displayed in different parts. By the use of the first two feeders described an imitation marble finish may be applied with or without the 45 feeder last described. By the use of the first and last feeders, omitting the second, an imitation wood finish may be applied.

It will be understood that the feeders may 50 be used in series and may be arranged in any desired order for producing designs of different general character.

In general my device embodies feeders for 55 producing three distinct classes of finish—the first a streaky finish, the second a variegated finish formed of drops running together in different forms, and the third a finely-spotted or veiled finish.

It is plain that the details of construction 60 of my device may be altered in numerous ways without departing from the spirit of my invention. I therefore do not confine myself to such details.

What I claim as my invention, and desire 65 to secure by Letters Patent, is—

1. In an apparatus of the class described, the combination of a tank containing a flowing supporting liquid; a paint-feeder having its feeding end in contact with the surface of said liquid, and adapted to feed the paint 70 upon said surface in the form of a streaked film; a second feeder having a vibratory motion adapted to throw the paint in scattered drops upon said surface; and a third feeder adapted to throw a fine spray of paint upon 75 said surface; substantially as and for the purposes specified.

2. In an apparatus of the class described, the combination of a tank containing a flowing supporting liquid; a paint-feeder having 80 its feeding end in contact with the surface of said liquid, and adapted to feed the paint upon said surface in the form of a streaked film; and another feeder having a vibratory motion adapted to throw the paint in scattered drops upon said surface; substantially 85 as and for the purpose specified.

3. In an apparatus of the class described, the combination of a tank containing a flowing supporting liquid; a paint-feeder having 90 its feeding end in contact with the surface of said liquid, and adapted to feed the paint upon said surface in the form of a streaked film; and another feeder adapted to throw a fine spray of paint upon said surface; sub- 95 stantially as and for the purpose specified.

4. In an apparatus of the class described, the combination of a tank containing a flowing supporting liquid; a paint-feeder having a vibratory motion adapted to throw the paint 100 in scattered drops upon said surface; and a paint-feeder adapted to throw a fine spray of paint upon said surface; substantially as and for the purpose specified.

5. In an apparatus of the class described, 105 the combination of a tank containing a flowing supporting liquid, and a paint-feeder having its feeding end in contact with the surface of said liquid, and adapted to feed the paint upon said surface in the form of a 110 streaked film, substantially as and for the purpose specified.

6. In an apparatus of the class described, the combination of a tank containing a flowing supporting liquid, and a paint-feeder having 115 a vibratory motion adapted to throw the paint in scattered drops upon said surface, substantially as and for the purpose specified.

7. In an apparatus of the class described, the combination of a tank containing a flowing supporting liquid, and a paint-feeder adapted to throw a fine spray of paint upon 120 said surface, substantially as and for the purpose specified.

Signed by me, at Chicago, this 28th day of 125 September, 1898.

JOHN H. DAVIS.
